UNITED STATES PATENT OFFICE.

BERTRAM P. ESTES, OF QUANAH, TEXAS.

AUTOMATIC TRAIN-STOP.

1,183,806.

Specification of Letters Patent. Patented May 16, 1916.

Application filed September 17, 1914. Serial No. 862,185.

To all whom it may concern:

Be it known that I, BERTRAM P. ESTES, a citizen of the United States, and a resident of the city of Quanah, in the county of 5 Hardeman, State of Texas, have invented certain new and useful Improvements in Automatic Train-Stops, of which the following is a specification.

This invention relates broadly to automatic train stops, and more particularly to 10 a system operable in connection with well-known air-brake systems to apply the air-brakes, and shut off the power when an accident of a predetermined character occurs.

15 The principal object of this invention is to provide a train control system by means of which by an application of an air-brake automatically shuts off the power.

A further and more particular object of 20 this invention is the provision of a mechanism constituting a control system, by means of which the air-brakes of a train are automatically set when any wheel is derailed.

A still further object of this invention 25 is the provision of a mechanism constituting a system, by means of which the derailment of any wheel of the train automatically sets the air-brakes and closes the throttle valve of the locomotive.

30 A still further object of this invention is to provide a discharge valve so constructed as to be held open, when once opened; and to provide frangible connections between the discharge valve and the car axle to prevent 35 breakage of the effective portions of the system should derailment of the truck detach the truck from the car.

Still other and further objects of this invention will in part be obvious and will in 40 part be pointed out in the specification herein-after following, by reference to the accompanying drawings in which like characters are used to represent like parts throughout the several figures thereof.

45 Figure 1 is a diagrammatic view illustrating the mechanism connecting the axles of the truck with a relief valve tapped into the train line. Fig. 2 is a detail view illustrating the position of the connection 50 operating with the axle. Fig. 3 is a detail view of the connecting links. Fig. 4 is a detail view showing a loop. Fig. 5 is a detail view illustrating one form of a discharge valve. Fig. 6 is a detail, cross-section view taken on line A—A of Fig. 5. Fig. 7 is a detail, diagrammatic, plan view

illustrating the portion of the connections for automatically operating the locomotive throttle valve. Fig. 8 is a detail, diagrammatic, elevational view illustrating the 60 mechanism for automatically operating the locomotive throttle valve. Fig. 9 is a plan, sectional view illustrating one form of three way cut-out valve, which may be used to cut out a portion of the system from operating.

Numerous devices have been designed to automatically apply the air-brakes in case of derailment. Such devices also include a discharge valve in the train line which is 70 operated when the wheels leave the rail. Heretofore, so far as applicant is aware, there have been no mechanisms devised for cutting off the power when a car wheel of a train has been derailed.

75 In such systems as have been designed, if a truck is thrown completely from beneath the car the opening and closing of the discharge valve occupies such a short interval of time that such systems are substantially ineffective. The system which will be hereinafter described more in detail by referring to the drawings is an improvement over automatic stops of this character, as have herein-before been specified, by insuring the continued operation of the system when once it is started, thereby making certain an effective application of the brakes and automatically closing the engineer's 80 throttle valve, thus preventing the locomotive from pulling out the draw-bars in the cars on which the brakes have been automatically set to emergency.

85 The invention herein disclosed also provides a system by means of which the throttle valve may be automatically closed by application of the brakes in service, and thus providing that under ordinary service conditions brakes will never be operated against the effective power of the engine.

100 Referring now to the drawings, and more particularly to Figs. 1 and 2, the train line pipe 1, in each car, is tapped at substantially the center thereof, and a discharge valve 2 is connected to the said train line by any convenient means, as for example, the short pipe 4. At each end of the car and preferably substantially above each axle a bell-crank 5, is attached to the car underframing, and in wood cars may be attached by 105 being bolted directly to the center sill by means of a bolt 6, which constitutes a pivot

for the bell-crank. A contractile spring 7, of considerable strength, is attached at one end to the car underframing, and at the other end to the bell-crank 5, and to the same end of the bell-crank is attached a link 8, by means of a pin and slot connection. These vertical links 8 carry at their lower end loops 9, which encircle the car axle 10 at substantially the mid-portion thereof. The connection between the loops 9, and the vertical links 8, is preferably a serrated connection including a bolt and a slot to allow for vertical adjustment, as is shown in detail in Figs. 3 and 4. The lower portion of the loops 9 is preferably provided with short, outstanding bearing cups 11, which are hollowed out as at 12, (Fig. 4) to provide receptacles which may be filled with hard oil or other convenient lubricant, to prevent excessive wear of the loop should it be drawn against the axle of the car while the car is in service. The discharge valve, (Fig. 5), may be of any relief valve type, but preferably comprises a valve provided with a stem 14, which carries a valve-head 15, which is normally seated in position by the compression spring, 16. Preferably the valve orifice when opened full is of the same diameter and the same area as the emergency port of the engineer's valve. This construction operates to set up a condition in the train line pipe, when the discharge valve is opened, which is exactly analogous to setting the engineer's valve to emergency. The discharge valve may be provided with a small bracket 17, which carries a short operating lever-arm 18. This arm is maintained in position between spring-pressed guide stops 19, which spring together over the top of the lever-arms 18, when the said lever-arm is operated to open the discharge valve. This structure retains the discharge valve open when once the system has been operated, until the stops 19 are manually released, and the lever 18 returned to normal position.

Again referring to Fig. 1, the lower ends of the bell-crank 5 are connected by means of links 20, with frangible springs 21, which are connected to the ends of the operating lever 18. These frangible springs 21 are of sufficient strength to insure the operation of the lever 18, but these springs 21 are constructed to break when excessive pull is reached. The purpose of these breaking is to prevent a truck de-railment from injuring or destroying the discharge valve and its connections.

Referring now more particularly to Figs. 7 and 8, wherein the engineer's throttle valve 22 is illustrated as being mounted on the locomotive boiler 24, in the usual manner, and is provided with the usual notched arc 26, in the notches of which the manually controlled dog 27, is adapted to be seated to

maintain the throttle in predetermined opened position. Intermediate the manual release lever 28, and the dog 27, is preferably introduced a small bell-crank, 29. An air-cylinder 30 is mounted adjacent the outer end of the throttle lever 22, by being attached to the locomotive structure in any convenient manner, and is provided with a piston 31, to which is connected the lever-arm 32, one end of which is mounted to rotate on the bracket 34, which is attached to the side of the locomotive boiler. The connection between the piston 31 and the lever-arm 32, is preferably a pin and slot connection, and a coil spring 35 is preferably mounted between the piston and the end of the cylinder to retain the parts in normal position. One end of the lever-arm 32, is connected to the small bell-crank 29 on the throttle lever. The air cylinder 30 is connected by means of a small pipe 36 with the locomotive brake cylinder pipe 37, which through the well-known and ordinary air-brake construction leads to the brake cylinders on the locomotive, which are ordinarily operatively connected with the train line pipe. The ordinary well known air brake construction previously referred to, and which is herein disclosed, is of a character wherein when pressure in the train line is reduced, air is automatically supplied to the brake cylinders on the locomotive, and also when the engineer's valve is operated to set the train brakes, air is supplied to the locomotive brakes. The locomotive brake cylinder pipe is also connected through an engineer valve by means of which the locomotive brakes, or the locomotive and the train brakes, are controlled.

From the foregoing, it is obvious that if the discharge valve 2, (Fig. 1), is operated to reduce train line pressure the brakes of the cars and also the locomotive will be set. The setting of the brakes on the locomotive introduces air under pressure directly to the locomotive brake cylinders. Since as above explained, the pipe 37 is directly connected with the locomotive cylinders, the pressure is the same in this pipe as it is in the cylinders and this pressure through the pipe 36 is communicated immediately to the air cylinder 30, thereby driving forward the piston 31 which through the lever-arm 32, and connections will pull the bell-crank 29 to release the dog 27, and further movement will pull the throttle lever to close the throttle. It will also be noted that an application of the air through the engineer's valve 38 will introduce pressure in the locomotive brake cylinder pipe 37, by means of the air cylinder 30, and connected parts, the throttle is automatically closed so that in running it is only necessary for the engineer to keep his hand upon the lever controlling engi-

neer's valve. In case it is desirable to cut out the automatic throttle control, as may sometimes be the case in switching, a small valve 39, is introduced in the pipe 36, to cut 5 out the automatic connection when desired.

The small valve 39, is preferably a three way valve as is illustrated in Fig. 9. This construction permits the air cylinder 30 to be open to atmosphere through the port 10 40, when it is desired to cut out the atmospheric operation in the cylinder 30. The compression spring 35, in the air cylinder 30, is not a strong spring so that when the three way cut-off valve, 39, is operated and 15 the air cylinder 30 open to atmosphere, the automatic mechanism does not interfere with the normal manual control of the throttle lever.

Having thus described my invention what 20 I desire and wish to claim is:

1. A device of the character described comprising in combination, a train line pipe of an air-brake system, a relief valve operatively connected with said train line pipe, 25 said relief valve being provided with a port having the same area as the emergency port, and connections intermediate said relief valve and the car axle, said connections including a frangible member constructed 30 to break under excessive stress.

2. In a device of the character described in combination, a train line pipe of an air-brake system, a relief valve operatively connected with said train line pipe, said relief 35 valve being provided with a port having the same effective area as the emergency port, connections intermediate said relief valve,

and the car axles to operate said valve when a car wheel is de-railed, and means operatively connected with the train line pipe 40 to close the throttle valve when said relief valve is operated.

3. In a device of the character described in combination, a train line pipe of an air-brake system, a relief valve operatively connected with said train line pipe, there being one relief valve for each car, and means operatively connecting each axle of the car with the said relief valve, said means including frangible members adapted to break 50 under excessive stress to prevent injury to the said relief valve and connected parts.

4. In a device of the character described in combination a power mechanism for propelling a train, said train including cars, 55 means carried by said cars for automatically rendering said power mechanism inoperative to propel said train when a car wheel is derailed, and a device for rendering said means inoperative at the will of an 60 operator.

5. In a device of the character described in combination a train comprising cars, a power mechanism for drawing said cars, and means for rendering said power mechanism 65 ineffective to draw said train when a car wheel is derailed, said means including devices carried by a car and operatively connected to certain of the wheels beneath the said car.
